CLAIM

The ornamental design for a cabinet pill dispenser, substantially as shown and described.

DESCRIPTION

FIG. 1 is a front and left side perspective view of a cabinet pill dispenser embodying the claimed design.

FIG. 2 is a front view of the cabinet pill dispenser of FIG. 1.

FIG. 3 is a rear view of the cabinet pill dispenser of FIG. 1.

FIG. 4 is a right side view of the cabinet pill dispenser of FIG. 1.

FIG. 5 is a left side view of the cabinet pill dispenser of FIG. 1.

FIG. 6 is a top view of the cabinet pill dispenser of FIG. 1; and,

FIG. 7 is a bottom view of the cabinet pill dispenser of FIG. 1.

In the drawings, the broken lines show portions of a cabinet pill dispenser that form no part of the claim.
